CLAIM

I claim the ornamental design for patient intravenous tube holder and organizer, as shown and described herein.

DESCRIPTION

FIG. 1 is a top perspective view of the patient intravenous tube holder and organizer according to a first embodiment of the invention.

FIG. 2 is a side elevation view of the patient intravenous tube holder and organizer.

FIG. 3 is another side elevation view of the patient intravenous tube holder and organizer, from the side opposite that in FIG. 2.

FIG. 4 is a top plan view of the patient intravenous tube holder and organizer.

FIG. 5 is a bottom plan view of the patient intravenous tube holder and organizer.

FIG. 6 is a front elevation view of the patient intravenous tube holder and organizer; and,

FIG. 7 is a rear elevation view of the patient intravenous tube holder and organizer.
